HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY.

RIP-STRIP CAN OR CONTAINER.

Application filed March 16, 1926. Serial No. 95,026.

My invention relates to cans or "tins" which are desirably, though not necessarily, of the vacuum type, that is, adapted for vacuum treatment for the more effective 5 preservation of the contents.

The object is to provide in a can of this or similar type, a hinged closure which is available for convenient use after the can has been initially opened, in order to properly 10 retain or protect the contents until the latter is exhausted. Cans of this type are usually provided with an integral rip strip which is torn away in the initial opening of the can. A further object of the invention 15 therefore, is to provide a suitable hinged closure in connection or combination with a can having a rip strip.

The characteristics and advantages of the invention are further sufficiently explained 20 in connection with the following detail description of the accompanying drawing, which shows one representative embodiment of the invention. After considering this example, skilled persons will understand that 25 many variations may be made, and I contemplate the employment of any structures that are properly within the scope of the appended claims.

Fig. 1 is a perspective view of the different parts embodying the invention in one physical form, approximately positioned, to explain the mode of assembly.

Fig. 2 is a perspective view of the upper part of the can or tin with the parts partially 35 assembled.

Fig. 3 is a side elevation of the complete, sealed can, with some parts sectioned.

Fig. 4 is a transverse vertical section.

Fig. 5 is a fragmentary horizontal section.

Fig. 6 is a perspective view of the complete can with the rip strip in process of removal.

Fig. 7 shows the can completely opened by removal of the rip strip and with the hinged cover thrown back to give access to the can contents.

The invention is especially designed or adapted for approximately "flat" cans which are intended for pocket use, being employed 50 for example, to contain smoking tobacco in

small quantities for pocket carrying and use of pipe smokers; and as here specifically embodied the invention is in the form of a flat tobacco can with rounded edge walls; but in the broader aspect of the invention it is 55 not limited as to the size or cross sectional form of the can.

The can body consists of a single body sheet 1, bent in flat tubular form with broad side faces 2 and rounded longitudinal edge 60 walls 3, and secured in that form by the usual side seam 4. Parallel score lines 5 are made, preferably on the inner face of the sheet, before it is bent to body form, and one of the sheet edges is formed with a 65 projecting tongue 6, which is a continuation of the rip-strip defined by the lines 5, this tongue being left free against the outer wall for application of a rip key 7, Fig. 6. Usually the bottom of the body is left open for 70 convenient filling, vacuum treatment and closure by the commodity producer or packer, the closure being effected by application of the usual bottom cap 8 secured in position by a lock seam 9. This procedure is 75 desirable because the top structure as now to be explained, is relatively complex, and top filling and closure by the commodity producer or packer would be relatively difficult and expensive. This procedure can, 80 however, be employed if considered necessary or desirable.

A collar is provided, shaped and dimensioned to have a close sliding fit within the upper part of the body 1. In one of its 85 broad walls 11, this collar is notched or cut to provide spaced hinge members 12, which are bent to eye form for the reception of a hinge pin. An inner cover member 13 is provided, of generally shallow, 90 dished formation, and of outline conforming to that of the can body and collar, and adapted to fit closely within the upper portion of the can body 1. This inner cover includes a main, flat wall 14, having an upturned marginal flange or wall 15, interrupted at 16 by a portion 17 which is cut to form spaced hinge members 18. The part 17 is turned down and the members 18 are bent in eye form. The eyes 18 are then 95 100

ready to be interspaced with the collar eyes 12 and connected thereto by the hinge pin 20, Figs. 2, 4, etc., whereupon the margin of the main wall 14 will rest upon the upper edge of the collar. The upper edge of the flange or wall 15 is usually slightly bent outward as at 21 to facilitate the cap crimping operation.

The collar with the attached hinged cover 10 is inserted in the upper end of the body, as shown in Fig. 4. Fig. 2 shows the collar partially inserted. It is moved down from the position there shown until the flange or wall 15 of the hinged cover telescopes within the upper portion of the body and the slightly flared periphery 21 of the cover wall rests upon or is substantially flush with the upper edge of the body, as shown in Fig. 4. The collar may be secured 20 in position in any suitable way, for example, by soldering. In the present example, preferred in some cases, the collar is secured by a crimping or beading operation, in which an outwardly convex bead 30 is 25 formed in the lower margin of the collar, and at the same time a mating bead 31 is formed in the can body, to securely lock the parts together and at the same time provide 30 a desirable outer appearance or "finish" of the can.

The outer or top cover cap 40 is then applied. This cap has a main wall 41 with a shallow side wall 42 terminating in a flat peripheral flange 43. The side wall 42 is 35 of course, conformed to the can outline and has a close push fit within the flange or wall 15 of the hinged cover 14. When so inserted the main wall 41 of the cap lies on the main wall 14 of the hinged cover, and 40 the flat flange 43 lies up on the upper edges of cover flange 15 and the body 1, and projects therefrom. The flat flange 43 is then rolled over or crimped by pressing or spinning operations to firmly clinch the edges 45 of the hinge and the main body in final closed form, as best shown in Fig. 4. The upper end or top of the can is thus completed and hermetically sealed, and as above stated, the bottom cap 8 is usually left off 50 so that the can may be filled with the desired commodity, vacuumized and capped, producing the complete package shown in Fig. 6, the rip strip, of course, being intact until removed by the consumer.

Fig. 6 shows the rip key 7 applied to the projecting tongue 6 of the rip strip and revolved sufficiently to wind a portion of the strip upon the key and tear this portion away from the can body. When the strip 55 is entirely torn off the cover structure including the top cap 40 and the hinged cover 13, secured together in the manner previously described, is accessible and free for opening by a hinge movement, as shown in Fig. 65 7. The act of tearing the rip strip pro-

duces a shallow side wall 50 now included in the cover structure, this being originally an integral part of the main can body, namely, the upper margin of the body, above the rip-strip. This wall 50, when the cover is closed, overlies the upper margin of the collar 10; or otherwise stated, the collar telescopes within this wall. Therefore, when the cover is shut, the can contents is securely held, but is easily accessible 70 when the cover is thrown back, as shown in Fig. 7 for removal of parts of the contents as often as desired, until the contents is exhausted.

It is especially to be noted that the closure 8 construction is very compact and none of the available space defined by the dimensions of the can body is wasted. In other words, the can has substantially the same cubic volume as an ordinary can of the same 8 dimensions.

It is evident from the preceding description, that an important function of the part 13, referred to as an "inner cover member", is to provide one convenient and practical 9 means for hingedly connecting the cover structure, considered as a unit, to the body, so that when the rip strip is torn off to initially open the can, the cover, including the cap 40 and the flange 50, remain in hinged 9 connection to the body, for convenient use as a movable closure. Prior to removal of the rip strip, however, the can top or cover (sometimes referred to as the "cap") 40 is seam-connected and hermetically sealed to the body, forming a vacuum-retaining closure, and the hinge structure is entirely enclosed, without requiring any irregular formation or enlargement of the body, and occupies a negligible part of the contents-space.

I claim:—

1. A can or similar container comprising a tubular body wall having a rip strip defined therein near one end, a collar within the body wall and underlying the rip strip, a cover hingedly secured to the collar, and a cap seamed to the cover and body wall to form a tight closure which becomes a hinged cover upon removal of the rip strip, whereupon a portion of the body wall remains attached to the hinged cover and overlaps the upper margin of the collar when the cover is closed.

2. A can of the vacuum type comprising a tubular body wall, a tubular collar in the upper portion thereof, the body wall having defined therein a rip strip overlying an upward portion of the collar, the collar having a hinge formation in one wall, a cover generally conforming to the cross sectional form of the body and having a side wall adapted to telescope therein and also having a hinge formation to co-operate with that of the collar, the edge of the cover side wall

being substantially aligned with that of the body, and a cap interlocked with the edges of the cover and the body walls to permanently secure them together, so that when 5 the rip strip is removed a remaining portion of the body wall is seamed to the cover structure and overlies the collar to form a tight closure openable by hinge movement to give access to the can contents.

10 3. A can having in combination a one-piece body and cover flange, comprising also a tearing strip integral with and arranged between the body portion and the cover flange portion, a collar secured to the body 15 and extending past the tearing strip into the cover flange to provide a neck upon which the cover flange may seat when the tearing strip is removed, the collar having a hinge part, a cover part seamed to the cover 20 flange, and a leaf having a hinge part cooperating with that of the collar secured to the cover and the cover flange by the seaming connection of cover and flange.

4. A can having in combination a one-25 piece body and cover flange, comprising also a tearing strip integral with and arranged between the body portion and the cover flange portion, a collar secured to the body and extending past the tearing strip into 20 the cover flange to provide a neck upon which the cover flange may seat when the tearing strip is removed, the collar having a hinge part, a cover including a leaf having a hinge part cooperating with that of the 35 collar, and an upstanding flange fitting within the cover flange, and a cup shaped member seated within the flange of the leaf and seamed to the leaf and cover flange.

Signed at Baltimore, in the county of Baltimore, and State of Maryland.

HENRY HERMANI.
